Specification of Letters Patent.

Patented Jan. 4, 1921.

Application filed July 26, 1919. Serial No. 313,483.

To all whom it may concern:

Be it known that we, JERRY H. KELLY and THOMAS W. PROSSER, citizens of the United States of America, residing at Chicago and Beaver Dam, respectively, in the counties of Cook and Dodge, respectively, and States of Illinois and Wisconsin, respectively, have invented certain new and useful Improvements in Apparel Apparatus, of which the following is a specification, reference being had therein to the accompanying drawing.

This invention relates to an apparel apparatus, and more especially to a hosiery inspecting and reversing structure.

15 The primary object of the invention is to provide a simple, comparatively inexpensive, and efficient apparatus by which, in a single operation, hosiery may be turned inside out, inspected, and automatically 20 counted, with a minimum amount of labor involved.

Another object of the invention is to provide a structure of the kind mentioned by which the fabric of the hosiery, for inspection purposes, may be momentarily stretched or opened up so that defects or imperfections therein may be easily discernible and by which structure the hosiery article, as it is being positioned on the same, may be turned 30 or reversed; and, if desired, there is associated with this structure a hosiery counting device which is operated during the operation thereof whereby, without mental effort on the part of the operator, the number 35 of hosiery articles inspected is automatically indicated. In some instances, there is associated with the counting device a signal—including, preferably, a bell—which, at a predetermined point or time of operation 40 of the structure, is actuated to notify the operator that a predetermined number of hosiery has been inspected.

Heretofore, it has been the rather general practice in hosiery mills to provide one or 45 another type of hosiery inspecting devices. For the most part, these have been made of wood and, in consequence, are more or less unsubstantial. These devices are generally operated only for effecting an inspection of 50 the hosiery article; and, by reason of the fact that they are constructed of wood, have surfaces which are more or less rough and, at best, make it difficult to efficiently place and inspect the hosiery article thereon.

The practice heretofore in vogue, in conjunction with these prior devices, was for the operator, after completing the inspection, to count a batch of goods inspected for the purpose of checking up the batch as to its completeness: In hosiery mills to-day, 55 the articles are handled and treated in lots of a dozen of the same. In other words, these articles are supposed to come to the inspector in batches or lots of a dozen each. The inspector, however, must check the 60 batch or lot to make certain that it includes the full dozen. This requires not only mental effort, but considerable time and trouble, with the result that the inspector is not able to handle as many lots of a dozen 65 as she might. To the end that the inspector's work may be facilitated and her counting and checking of the batches may be accomplished simultaneously with the operation of inspection, we have made it a 70 desideratum, in the present invention, to aggroup coacting instrumentalities whereby the three operations of turning the article inside out, inspecting the same, and counting it, are effected by the one device and 75 without requirement on the part of the inspector to count each article of the batch. In other words, it is a feature of the present invention to provide a combined inspecting, turning and counting structure, for use 80 in hosiery mills, whereby, with this single structure, an increased number of articles 85 may be daily handled by the inspector and with a desirable assurance of accuracy.

The invention involves other features, 90 some of equal importance to that just mentioned, and these will be made apparent in the description which follows hereinafter.

In order that the invention may be more readily comprehended, we have revealed it 95 in the accompanying drawings; but, as it involves certain fundamental features which may be combined or aggrouped in different ways, what is here disclosed is to be regarded as merely illustrative; in other 100 words, the structure, as herein revealed, may be considerably varied and modified without departing from the invention and without sacrificing any of these salient features or underlying principles.

105 In the drawings:

Figure 1 is a view in perspective of our device;

Fig. 2 is a view in end elevation thereof; Fig. 3 is a view in vertical longitudinal section of the same;

Fig. 4 is a view in vertical transverse section on the line 4—4 of Fig. 3;

Fig. 5 is a similar view on the line 5—5 of Fig. 3;

Fig. 6 is a view, on a somewhat exaggerated scale, of a portion of the inspecting member, with a stocking thereon to show the effect of the particular dimensions and form of the member; and

Fig. 7 is a view in detail of some parts of the structure.

Referring to these drawings, the reference-numeral 1 designates a bracket or standard which, in this instance, may be secured to a table or other sustaining structure. This standard includes a base-portion 2, an upright portion 3, a bearing portion 4, and a counter-sustaining portion or arm 5. In the bearing portion 4 are bearings 6.

Sustained by the standard and freely rotatable in the bearings is an inspecting member designated, generally, by 7. This includes a shaft portion 8, a cylindrical portion 9, and a fabric opening-up portion 10. This last-mentioned portion is preferably made of aluminum because of the characteristic attribute thereof for producing or effecting what is practically a self-lubricating action when fabric is placed thereon. In other words, the aluminum, possessing a smooth surface, and having the aforementioned characteristic attribute of facilitating the movement of fabric as the same may be placed or stretched over such surface, we take advantage of this condition and effect a new function in connection therewith, as will be presently hereinafter explained.

The member 10, preferably and as shown, is of greater widthwise dimension than is its thickness; and this presents oppositely-disposed sides 11, which are preferably arcuate shape or curved, and provide a member which is relatively thin in cross section. The edges 12 are, preferably and as shown, somewhat rounded and are reduced in thickness considerably in comparison with the thickness of the medial portion of the member. The edge 13 of the end of the member is similarly formed.

The cylindrical portion 8 has formed at its end a circular terminal 14; and this is adapted to be secured, as by screws or bolts 15, to a pawl-carrying member 16 to which the shaft 8 is attached. The member 16 is provided with two oppositely-disposed bosses 17 in which are located two spring-actuated pawls 18, the upper end of each of which is formed with a beveled surface 19 and with a cutout 20, the function of which will presently be described.

Rotatably mounted on the counter-sus-

tering disk 21 provided with serrations 22 on its periphery. Juxtaposed to each serration is a number or index 23, there being, in this instance, twenty-four of these disposed in a circular line. Upstanding from the portion 70 5 and adapted to register with the serration 22 and its respective index 23 is a pointer 24. Thus, on the disk 21 and the standard are coacting means to effect an accurate register or counting. The teeth of the serration 22 are arranged to be engaged by the pawls 18 so that, when the member 10 is moved, the pawls are brought into register with the serrations. The beveled formation 19 on the pawl permits it to latch by a serration without effecting rotation of the disk 21, but the cutout 20 presents a disk-engaging abutment 25 which will engage a tooth on the disk and rotate it one point or increment.

On the outer face of the counter-disk is a cam-formation 26 adapted to be engaged to the end of a bell-ringing element 27, this being secured to the bell support 28. It will now be understood that when the cam 26, 90 during rotation of the counter-disk, engages the element 27, it will tension it so that when it is disengaged from the cam the looped portion 29 of the element 27 will impinge against the bell and ring it. This ringing 95 will occur, preferably, when the pointer 24 is in register with the index-number "24," on the disk 21.

Operation: If the device is to be used as a turning or reversing instrumentality, the 100 inspector places a portion of the inner surface of the article on the end of the member 10 and pulls the same toward the connected end of the member. By reason of the smooth surface of the form and its particular dimensions and formation, the article is reversed or turned inside out simultaneously with its being positioned on the member. The circumference of this member is preferably somewhat greater than that of an un-stretched hosiery article; and, by reason of this fact, the article is slightly stretched so as to open the fabric thereof and permit a ready and accurate inspection and the detection of imperfections, holes, etc. A feature of the present invention resides in the fact, first, that the member is made of aluminum, which permits the fabric to slide on its surface with great facility; and, secondly, that the member is of a circumference or 110 transverse dimensions such that it effects a stretching or opening up of the fabric. 115

When the hosiery article is disposed on the member, the inspector manually turns it to examine the opposite side. As the 125 member is turned in one direction, one of the pawls 18 is positioned in register with a serration in the disk 21, and when the abutment 25 engages a tooth of the serration, it turns the disk one point. When the 130

member is turned in the opposite direction, the pawl latches by the teeth on the disk 21 and the latter remains unturned. As the operation continues, the inspector will eventually have turned the disk 21 until the pointer 24 is about to register with the counter number "24" on the disk 21. As that condition develops, the cam 26 engages the bell-ringing element 27 so that, when the pointer 10 and counter number "24" are brought into register, the bell is rung, and the inspector is thereby advised that twenty-four articles have been inspected, or inspected and turned, as the case may be. If, therefore, 15 any particular batch which comes to the inspector includes too few or too many articles, the inspector, with this device, will be able to detect that fact without having to handle the goods separately after inspection 20 to count them.

In actual practice with this device, it has been found that an inspector is able to turn, inspect, and count a very much greater number of hosiery articles, in a day's time, and 25 without any increased effort on her part in the operation. In addition, a better inspection can be effected. Still, again, an accurate counting of the hosiery articles is effected by the device while the operator is 30 operating it and without any effort on her part in that direction.

We have, herein, revealed the invention in a particular embodiment; but it is to be understood that we do not restrict ourselves 35 thereto, nor to the details which may have been described herein, excepting insofar as such details may be recited in the appended claims.

What we claim is:

- 40 1. A hosiery-handling structure including a rotatable hosiery-reversing and inspecting instrumentality of a width-wise dimension greater than its thickness, a hosiery counting device, a support common 45 to the inspecting instrumentality and device, and co-acting means carried by the instrumentality and device whereby by the movement of the instrumentality an indicating action of the device is effected.
- 50 2. A hosiery-handling structure including a rotatable hosiery-reversing and inspecting instrumentality relatively thin in cross section and having curved sides and rounded edges, a hosiery-counting device, a standard common to the instrumentality and device for sustaining them in normally unengaged position, and co-acting means carried by the instrumentality and device whereby by the turning of the instrumentality the counting device is periodically operated.
- 55 3. A hosiery-handling structure including a rotatable hosiery inspecting instrumentality of greater width than thickness and having curved sides and reduced,

rounded edges, a hosiery-counting device associated therewith and operated by the turning of the inspecting-instrumentality to indicate the number of hosiery-articles inspected thereon, a standard common to and 70 for supporting the instrumentality and device, and co-acting means carried by the instrumentality for effecting co-operation therebetween.

4. A hosiery-handling structure including a rotatable hosiery inspecting instrumentality of greater width than thickness and having curved sides and reduced, rounded edges, a hosiery-counting device associated therewith and rotatable in a clockwise direction by the turning of the inspecting-instrumentality to indicate the number of hosiery-articles inspected thereon, and a standard for sustaining said instrumentality and device in normally unconnected relation, 80 and means carried by the instrumentality and engageable with the device periodically.

5. A hosiery-handling structure including a supporting-standard, a hosiery inspecting and reversing member rotatably sustained thereby and of greater width than thickness and having fabric opening-up surfaces, and made principally of aluminum to provide a self-lubricating face on each surface, a hosiery counting device on the standard, and coacting means on the device and member for operating the same at each turning of the member; the standard being common to the inspecting member and counting device for sustaining them in normally unengaged relation.

6. A hosiery-handling structure including an upright supporting-standard, bearings therein, a hosiery inspecting and reversing member sustained by the standard 105 and freely rotatable in the bearings, of greater width than thickness, and made principally of aluminum to provide a self-lubricating, fabric opening-up surface, spring-pressed pawls carried by the member, and a counter-disk sustained by the standard and periodically engageable by the pawls to rotate it in one direction.

7. A hosiery-handling structure including an upright supporting-standard, bearings therein, a hosiery inspecting and reversing member sustained by the standard and freely rotatable in the bearings, of greater width than thickness, and made principally of aluminum to provide a self- 115 lubricating, fabric opening-up surface, spring-pressed pawls carried by the member, a counter-disk sustained by the standard in normally unengaged relation to the inspecting member and periodically engageable by the pawls to rotate it in one direction, 120 and a pointer stationary on the standard and associated with the counter-disk.

8. A hosiery-handling structure including an upright supporting-standard, bear- 130

ings therein, a hosiery inspecting and reversing member sustained by the standard and freely rotatable in the bearings, of greater width than thickness, and made 5 principally of aluminum to provide a self-lubricating, fabric opening-up surface, spring-pressed pawls carried by the member, a counter-disk sustained by the standard in normally unengaged relation to the inspecting member and periodically engageable by the pawls to rotate it in one direction, a pointer stationary on the standard 10 and associated with the counter-disk, a bell

sustained by the standard and stationary relative to the disk, and means carried by 15 the disk for operating the bell at a predetermined position of the disk when operated by the inspecting-member.

In testimony whereof we affix our signatures in presence of two witnesses.

JERRY H. KELLY.
THOMAS W. PROSSER.
